UNITED STATES PATENT OFFICE.

CLARKE V. FOLAND, OF BLUEFIELD, WEST VIRGINIA.

APPARATUS FOR DISCHARGING COLLAPSIBLE TUBES.

1,228,309.

Specification of Letters Patent.

Patented May 29, 1917.

Application filed March 27, 1915. Serial No. 17,840.

To all whom it may concern:

Be it known that I, CLARKE V. FOLAND, a citizen of the United States, residing at Bluefield, in the county of Mercer and 5 State of West Virginia, have invented certain new and useful Improvements in Apparatus for Discharging Collapsible Tubes; and I do hereby declare the following to be a full, clear, and exact description of the 10 invention, such as will enable others skilled in the art to which it appertains to make and use the same.

This invention relates to devices for discharging or extracting the contents from 15 collapsible tubes, and the primary object of the invention is to provide a device of this nature which will squeeze a collapsible tube, from the closed end, toward the open end for efficiently forcing the contents out 20 of the tube, and further to provide a device which is an improvement over the application for Letters Patent, Serial No. 863,500, filed September 25, 1914.

Another object of this invention is to 25 provide a flexible ribbon, which has a buckle secured to one end thereof, for detachable connection with the closed end of a collapsible tube, for drawing the same downwardly between a pair of compressing 30 rollers, upon the winding of the flexible ribbon or member about a third roller which forms a key roller for drawing the closed end of a collapsible tube downwardly 35 between the compressing rollers for discharging the contents of the tube from the open end of the same.

A further object of the invention is to provide means for preventing reverse rotation of the key roller.

40 The apparatus further forms a support for holding collapsible tubes in a vertical position, thereby preventing the leakage or dripping of the contents of the tube.

With the foregoing and other objects in 45 view this invention consists in such novel features of construction, combination and arrangement of parts as will be hereinafter more fully described, illustrated in the accompanying drawings and claimed.

50 In describing the invention in detail reference will be had to the accompanying drawings wherein like characters designate like or corresponding parts throughout the several views, and in which:—

55 Figure 1 is a side elevation of the im-

proved apparatus for discharging collapsible tubes,

Fig. 2 is a cross sectional view through Fig. 1,

Fig. 3 is a detail view, showing the flexible member connected to the collapsible tube, and

Fig. 4 is a cross sectional view on the line 4—4 of Fig. 3.

Referring more particularly to the drawings, 1 designates the body of the apparatus as an entirety, which has a pair of compression rollers 2 and 3 rotatably supported thereby, in parallel spaced relation with each other, as is clearly shown in 70 Fig. 2 of the drawings. The supporting body 1 has a third roller 4 rotatably supported thereby, and positioned beneath the rollers 2 and 3. The roller 4 is provided with a diametrically disposed slot 5 extending longitudinally therein. The roller 4 has a stub shaft 6 formed upon one end thereof, which projects out of one of the sides of the body 1 and has a head 7 mounted upon its outer end, to which is 80 connected a plurality of radially extending rods 8, provided for facilitating the manual rotation of the shaft 6 and the roller 4.

The shaft 6 has a ratchet 9 mounted thereon, the peripheral ratchet teeth of 85 which are provided for engagement with the pointed end 10 of the pawl 11. The pawl 11 is pivotally supported, as at 12, to the body 1, and it has its end 13, opposite to the pointed end thereof, weighted, 90 for holding the pointed end 10 of the pawl in engagement with one of the peripheral teeth of the ratchet 9, for preventing a reverse rotation of the shaft 6 and the roller 4.

The roller 2 has a stub shaft 14 secured to its ends which are rotatably supported in arcuate slots 15 formed in the ends of the body, to permit of the movement of the rollers outwardly from the roller 3, as is indicated in dotted lines in Fig. 2 of the drawings, for facilitating the removal of a flexible tube, indicated at 16, from between the rollers.

The lower closed end 17, of the flexible 105 tube 16, is bent about the central cross bar 18 of a buckle structure 19. The buckle structure 19 is secured to a flexible ribbon 20, as is shown at 21, in Fig. 4 of the drawings, and it extends downwardly therefrom, hav- 110

ing its lower end inserted through the opening 5, which is formed in the key roller 4, for winding the flexible ribbon 20 about the key roller 4, upon rotation of the latter, for 5 forcing the flexible tube downwardly between the compressing rollers 2 and 3. The buckle structure 19 includes the central rail or bar 18, about which the closed end of the flexible tube is mounted, an upper cross bar 10 22, and the lower cross bar 23 to which the ribbon or flexible member 20 is connected. The top cross bar 22 engages the flexible tube and lies in flat abutment therewith, for providing a firm and secure connection be- 15 tween the flexible tube and the ribbon 20. The end of the flexible tube is bent upwardly, so that the inner surface of the top cross bar 22 will engage the same, and force it against the facing side of the tube, as 20 is clearly shown in Fig. 4 of the drawings.

The buckle structure 19 is curved to conform to the curvature of the key roller 4, so that it will pass upon the roller in a level manner, eliminating an outstanding obstruction, such as would be formed by a straight buckle.

When it is desired to discharge the contents from the tube 16, the lower closed end 17 of the same is attached to the buckle structure 19, as heretofore described, and the buckle and the ribbon 20 are passed downwardly between the rollers 2 and 3, after which the lower end of the ribbon is inserted through the slot 5 formed in the key roller 30 4. Rotation of the key roller 4, will wind the ribbon 20 about the roller, and force or draw the flexible tube 16 downwardly between the compressing rollers 2 and 3, squeezing the tube and forcing the contents 35 of the same upwardly out of the open end of the tube. The ratchet 9 is disposed so as to permit of a winding rotation of the ribbon 20 upon the roller 4, and the pointed end 40 10 of the pawl 11 engaging the peripheral teeth of the ratchet, will prevent an unwinding rotation of the roller, and hold the flexible tube 16 firmly between the rollers 2 and 3, so that upon a limited rotation of the 45 roller 4, a part of the contents of the flexible 50 tube may be forced therefrom.

When it is desired to remove the tube 16 from connection to the squeezing apparatus, the roller 2 may be moved upwardly and outwardly, by moving the stub shaft 14 upwardly within the arcuate slot 15, which 55 will position it away from the roller 3, and the pawl 11 operated for movement out of engagement with the ratchet 9, after which the roller 4 may be rotated in an unwinding position, until the buckle 19 has passed upwardly between the rollers 2 and 3, at which point the lower closed end 17 of the tube may be disconnected from the buckle, and another tube attached thereto.

In reducing the invention to practice, certain minor features of construction, combination, and arrangement of parts may necessitate alteration to which the patentee is entitled, provided such alterations are comprehended within the scope of what is 60 claimed.

What is claimed is:—

The combination with a collapsible tube, of a body, a pair of parallel compression rollers journaled to said body and receiving 75 the tube, means by which one of the rollers may be moved toward and from the other roller, a roller journaled in said body and having a longitudinally extending groove therein, said tube having its lower end bent 80 upon itself to form a loop, a central bar extending through the loop, curved side members formed on the ends of the bar, an upper bar connecting the upper ends of the members and bearing against the ends of the tube 85 to bind it against the body of the tube, a lower bar connecting the lower ends of the members, and a ribbon passed about the lower bar and having its ends inserted through the longitudinally extending groove 90 to establish a flexible connection between the tube and the last mentioned roller for drawing the tube through the compression rollers upon rotation of the roller.

In testimony whereof I affix my signature 95 in presence of a witness.

CLARKE V. FOLAND.
